UNITED STATES PATENT OFFICE.

OSCAR A. SMITH, OF CLEVELAND, OHIO, ASSIGNOR TO THE NATIONAL ACME COMPANY,
OF CLEVELAND, OHIO, A CORPORATION OF OHIO.

MACHINE-SCREW.

1,330,098.

Specification of Letters Patent. Patented Feb. 10, 1920.

Application filed May 16, 1919. Serial No. 297,692.

To all whom it may concern:

Be it known that I, OSCAR A. SMITH, a citizen of the United States, residing at Cleveland, in the county of Cuyahoga and 5 State of Ohio, have invented certain new and useful Improvements in Machine-Screws, of which the following is a specification.

This invention relates to machine screws, 10 such as fillister head or round head or collar machine screws, the object of the invention being to provide a headed machine screw of this character having a very strong tang or driving portion for the reception 15 of a suitable mating wrench therefor, and in which machine screw there are no sharp corners to form a good starting point for breaking or peening, and which is simple in construction and inexpensive to manufacture.

In my prior Patent No. 1,269,971 dated June 18, 1918 I provided a headless machine screw with an improved driving portion, in which the concaved recesses at the sides of 25 the tang or driving portion were of greater diameter than the convexed driving portions at the margins of such convexed driving portions.

In the present improvement however, the 30 diameter of the recesses is materially smaller than the arc of the convexed driving portions at the margins of the head notwithstanding which, however, a driving tool such as is shown in the present improvement, 35 can be used with equal facility to drive the set screw shown in my said patent, which important result has been worked out after considerable experimentation.

In the drawings accompanying and forming 40 part of this specification, Figure 1 is a top view of a round head machine screw; Fig. 2 is a top view of a fillister head machine screw; Fig. 3 is a side view of a round head machine screw; Fig. 4 is a 45 side view of a fillister or oval head machine screw; and Fig. 5 is a perspective view of a headed machine screw and the mating end of its wrench.

Similar characters of reference indicate 50 corresponding parts in the several figures of the drawings.

There are of course many forms of headed machine screws in common use, practically all of which have a common screw driver

slot, and it is of course difficult to tighten 55 or set them home strong enough with a screw driver and various attempts have been made to improve these styles of machine screws, but for various reasons they have not been found entirely satisfactory. 60 By means of the present improvement however, the head of the machine screw is exceptionally strong, and while the wrench or driving tool is sufficiently strong to properly set the screw home for all practical requirements, yet the wrench is the weaker member and it should be at least of substantially no greater strength than the driving portion 65 of the screw and there are no sharp corners either on the wrench or on the tang to afford 70 opportunity for breakage or peening off.

This improved machine screw shown in the drawings comprises a head 2 and a threaded shank 3, the head in Fig. 1 being known as a round head machine screw 75 while that in Fig. 2 is known as a fillister or oval head machine screw. Formed in the head are a pair of radial recesses 4, each having parallel straight sides 5 and a curved inner face 6 terminating short of the vertical axis of the head thereby forming a pair of connected convexed portions 7, the arc of each of which at the margin of the head 8 is greater than the diameter 9 of said recesses and the depth of which recesses is 80 materially less than the depth of the head. Thus in the present improvement the convexed driving portions of the tang have diameters materially greater than the diameter of the radial recesses and yet the 85 structure is such that the driving tool herein shown, and which is adapted to fit such radial recesses, can be used with equal facility in driving the set screw shown in my said patent, so that it is unnecessary to furnish a special driving tool for the set screw of said patent and also for the machine screw of the present improvement.

The wrench shown in Fig. 5 is provided 95 with a groove 10 adapted to mate with the tang or driving member of this improved machine screw, which groove forms a pair of driving portions 11 having generally the shape of the radial recesses of the driving tang of the headed machine screw.

From the foregoing, it will be observed 100 that the radial recessed formation of the driving tang of the machine screw and the

convexed formation of the wrench or driving tool provides a very effective interlock between these two members, so that the possibility of twisting off the driving portion 5 of the screw is eliminated. Not only this, but the turning movement of the wrench or driving tool, should there be any play between its driving portions and the tang of the machine screw, will cause the interlocked 10 portions to effectively engage each other to prevent slippage of one relatively to the other and thus avoid the twisting off of the tang or the eating off of the edges thereof.

The gist of the present improvement is 15 the provision of a headed machine screw having a reinforced driving portion which will be as strong as, if not stronger than the means for tightening the screw, so that the heads cannot become peened or broken, and 20 which will avoid the common form of slot usually used, and which form of machine screw cannot be readily tightened home because of weakness in the screw driver.

In the present improvement, the screw 25 and driver by means of the constructions herein shown and described, have at least substantially equal strength. In other words, one is as strong as the other, as can be readily seen by a careful inspection of 30 the drawings, in which the arrows indicate the points where the greatest strain of the driver upon the screw comes. At this point the driving tang or portion of the screw is the thickest.

I claim as my invention:

1. A machine screw having a round head provided with straight sides, said head having in the top thereof a pair of radial recesses, each having parallel straight sides and a curved inner face terminating short of the 40 vertical axis of the head to form a pair of connected convexed portions, the greatest diameter of each of which is greater than the greatest diameter of either of said recesses, and the depth of each of which recesses is less than the depth of said round head.

2. A machine screw having a curved head provided with straight sides, said head having in its top a pair of opposed radial recesses to form a driving portion or tang gradually thickening outward from the axis of the screw to the margin of the head whereby the driving portion or tang is of greater width at the margin of the head 55 than it is at the axis thereof thereby to bring the strain of setting the screw on the thickest portion of the tang and the arc of which thickest portion of the tang is materially greater than the arc of said radial 60 recesses and the depth of each of which recesses is materially less than the depth of said straight sides of the head.

Signed at Cleveland, in the county of Cuyahoga and State of Ohio, this 12th day of 65 May, 1919.

OSCAR A. SMITH.
